(57) **CLAIM**

The ornamental design for an electronic mouse, as shown and described.

DESCRIPTION

FIG. 1 is a perspective view of an electronic mouse showing my new design;

FIG. 2 is a side view thereof;

FIG. 3 is an opposite side view thereof;

FIG. 4 is a front view thereof;

FIG. 5 is a rear view thereof; and,

FIG. 6 is a top view thereof.

The broken line showing of a scroll wheel in FIGS. 1-4 and 6 is for illustrative purposes and forms no part of the claimed design. The broken line showing of a cable inlet in FIGS. 1 and 4 is for illustrative purposes only and forms no part of the claimed design. The unshown bottom of the electronic mouse forms no part of the claimed design.
